No. 36,863.

Patented March 29, 1904.

UNITED STATES PATENT OFFICE.

JOSEPH LEVI, OF NEW YORK, N. Y.

DESIGN FOR BRAID.

SPECIFICATION forming part of Design No. 36,863, dated March 29, 1904.

Application filed February 23, 1904. Serial No. 194,961. Term of patent 3½ years.

To all whom it may concern:

Be it known that I, JOSEPH LEVI, a citizen of the United States, residing at the borough of Manhattan, in the city, county, and State of New York, have invented a new, original, and ornamental Design for Braid, of which the following is a specification, reference being had to the accompanying drawing, forming part thereof.

The figure is an elevation of a piece of braid, ¹⁰ showing my ornamental design.

I claim—

The ornamental design for braid, substantially as herein shown.

JOSEPH LEVI.
